UNITED STATES PATENT OFFICE.

DAVID BRICKMAN, OF PASADENA, CALIFORNIA.

PORTABLE COMBINATION REVOLVING BAKER'S GAS-OVEN.

1,298,876.

Specification of Letters Patent.

Patented Apr. 1, 1919.

Application filed September 5, 1917. Serial No. 189,866.

To all whom it may concern:

Be it known that I, DAVID BRICKMAN, a citizen of Russia, residing at Pasadena, in the county of Los Angeles and State of California, have invented new and useful Improvements in Portable Combination Revolving Bakers' Gas-Ovens, of which the following is a specification.

My object is to improve the lay-out and 10 details of construction of a portable combination revolving baker's gas oven.

The leading feature of my invention is the provision of an improved construction whereby the oven may be readily knocked 15 down, transported, and set up again.

Figure 1 is a side elevation of a portable combination revolving baker's gas oven involving the principles of my invention, and looking in the direction indicated by the 20 arrow —1— in Fig. 2.

Fig. 2 is an end elevation looking in the direction indicated by the arrow —2— in Fig. 1, parts of the wall being broken away to show the interior details.

Fig. 3 is a top plan view of one of the gas burners removed from the furnace.

Fig. 4 is an enlarged vertical cross-section through the gas burner on the line 4—4 of Fig. 3.

Fig. 5 is a vertical sectional detail on the line 5—5 of Fig. 4.

My oven is constructed without any bottom as it is supposed to set on a granitory floor or upon the ground or other suitable 35 non-combustible floor. The end frames 1 and 2 and the center frame 3 are constructed of angle iron and are substantially alike. The lower side walls 4 and 5 are sheet iron removably bolted to the frames 1, 2 and 3, 40 said walls being slightly flaring in end elevation and extending slightly more than halfway to the top. The upper side walls 6 and 7 are removably bolted to the upper part of the frames, said walls being inclined inwardly from the upper edges of the walls 4 and 5, and the top plate 8 is removably bolted to the frames and connects the upper edges of the walls 6 and 7. End plates 9 and 10 are removably bolted to the frames 45 1 and 2 and extend upwardly to the level of the upper edges of the plates 4 and 5. The end plates 11 and 12 are connected to the upper edges of the plates 9 and 10 by hinges 13 and are removably bolted to the 55 upper parts of the frames 1 and 2. Door

openings are formed between the lower edge of the plate 6 and the upper edge of the plate 4, and doors 14 are connected to the upper edge of the plate 4 by hinges 15 so as to close these door openings. Doors 60 13 are inserted into the plate 4. A partition 17 is secured to the frame 3, thus dividing the oven into two chambers, 18 and 19, each chamber comprising a complete and independent baking compartment. It will 65 only be necessary to show and describe the details of the apparatus in the compartment 19.

A bearing 20 is fixed to the partition 17 and a similar bearing is formed through the 70 end plate 12. The shelf shaft 21 is inserted through the end plate 12 into the bearing 20, said shaft being slightly above the upper edge of the plate 4 so as to be visible through the door 14. Arms 22 are removably fixed 75 upon the shaft 21 and extend radially, said arms being concentrically connected by braces 23 so as to form one side of a Ferris wheel just inside of the bearing 20, and a corresponding Ferris wheel construction 24 80 is located just inside of the end wall 12. The oven shelves 25 have hangers 26 extending upwardly from their ends and pivotally connected to the outer ends of the arms 22 so that the shelves will hang level 85 like a Ferris wheel car as the shaft 21 rotates. A worm gear 27 is fixed upon the outer end of the shaft 21, and a worm shaft 28 is mounted along the upper edge of the end plate 10 and has a worm pinion 29 in 90 mesh with the gear 27, and a belt pulley 30 for receiving power from a motor or other suitable source. A notch 31 extends upwardly from the lower edge of the end plate 10 and the base of the burner 32 is adapted 95 to slide in and out through this notch. A door opening 33 is formed in the end plate 10 above the notch 31, and a sliding door 34 is provided for the opening.

The details of the burner 32 are as follows:

A rectangular frame 35 is constructed of angle iron and mounted upon legs 36, and a foraminous plate 37 is mounted horizontally in the frame. Burner pipes 38, 39, 40 105 and 41 are inserted horizontally through the vertical webs of the frame 35 above the foraminous plate 37, said pipes having ori- fices 42 immediately above the plate 37 and said pipes being controlled independently 110

22

by gas cocks 43, 44, 45 and 46. Three cross pieces 47 are inserted into the frame 35 so as to make bases for the four burners, and preferably there will be a sheet 37 for each burner. Each burner is provided with an independent mixing chamber and screen 48. The mixing chamber comprises a rectangular vertical casing 49 adapted to fit within a section of the frame 35 and form close joints with the foraminous plate 37, and the partition walls 50 and 51 are inserted into the casing 49 to divide the casing into three independent mixing chambers, there being a set of nozzle openings 42 in the burner pipes 10 for each mixing chamber. A foraminous plate 52 is mounted on top of the casing 49 and forms the burner screen. When one of the gas cocks 43, 44, 45 or 46 is opened the gas will be discharged through the corresponding nozzles 42 horizontally in opposite directions from the pipe and above the plate 37. Fresh air will pass into the mixing chambers through the plate 37 and mix with the gas and will pass upwardly through the screen 52 and burn on top of the screen. The screen 52 is large and provided with very small perforations so that a highly explosive mixture may be formed in the mixing chambers and burn on top of the screen 25 without burning back into the mixing chambers. There will be no gas pressure in the mixing chamber but on the contrary the combustion on top of the screen 52 will produce a draft of fresh air through the plate 37 to mix with the gas in the mixing chambers. The burner base consisting of the frame 35, legs 36, plates 37, and gas pipes 38-41 may be removably inserted through the notch 31, then the casing 49 may be inserted through the lower opening 33 and placed upon the base. Of course, the supply pipe 53 may be broken by a union at any desired place.

A water coil 54 is mounted in the chamber 45 19 against the partition wall 17 and around the burner 32, and the coil is provided with a drain-cock 55 which leads from the lower part of the coil, and a blow-off 56 is provided at the upper end of the coil to discharge steam into the chamber, said blow-off being controlled by a valve 57.

The burner 32 extends substantially the whole length of the compartment 19, and each section 38, 39, 40 and 41 of the burner 55 may be turned on, shut off, or controlled to a nicety, thereby insuring an even heat of any desired capacity. The fire and baking process may be observed through the door 16, and the baking may be inserted or removed 60 through the door 14. A canopy and

flue 58 may be mounted above the oven to carry off the heat.

In a companion application for gas burners, filed August 29, 1918, Serial No. 251,974 I have shown, described and claimed 65 the burner by itself, and I do not wish to make such claims herein.

Various changes may be made in the arrangement and details of construction without departing from the spirit of my invention as set up in the following claims.

I claim:

1. A portable gas oven comprising end frames constructed of angle iron, lower side walls removably bolted to the angle iron; 75 said walls being flaring in end elevation and extending more than half way to the top, upper side walls removably bolted to the angle iron; said upper side walls being inclined inwardly from the upper edges of the lower side walls; a top plate removably bolted to the angle iron, lower end plates removably bolted to the angle iron and extending to the upper edges of the lower side walls, upper end plates connected to the upper edges of the lower end plates by hinges and removably bolted to the angle iron; there being a door opening between the lower edge of one upper side wall and the upper edge of the corresponding lower side 90 wall and extending the length of the side walls; and a door hinged to the upper edge of the lower side wall for said door opening.

2. A portable gas oven comprising end frames constructed of angle iron, lower side walls removably bolted to the angle iron; 95 said walls being flaring in end elevation and extending more than half way to the top; upper side walls removably bolted to the angle iron; said upper side walls being inclined inwardly from the upper edges of the lower side walls; a top plate removably bolted to the angle iron, lower end plates removably bolted to the angle iron and extending to the upper edges of the lower side 105 walls, upper end plates connected to the upper edges of the lower end plates by hinges and removably bolted to the angle iron; there being a door opening between the lower edge of one upper side wall and the upper edge of the corresponding lower side wall and extending the length of the side walls; a door hinged to the upper edge of the lower side wall for said door opening; there being a notch in the lower edge of one end plate; and a burner mounted to slide in and out through this notch.

In testimony whereof I have signed my name to this specification.

DAVID BRICKMAN.
